CLAIM

The ornamental design for a battery, as shown and described.

DESCRIPTION

This application incorporates by reference in its entirety each of the following U.S. Design patent application Nos., filed on the same day herewith:

Ser. No. 29/654,658, titled "Aerial Vehicle"

Ser. No. 29/654,663, titled "Camera"

Ser. No. 29/654,665, titled "Camera with gimbal"

FIG. 1 is a top front perspective view of a battery showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
